UNITED STATES PATENT OFFICE.

HENRY GROSS, OF TIFFIN, OHIO.

CAR-COUPING.

SPECIFICATION forming part of Letters Patent No. 276,681, dated May 1, 1883.

Application filed September 2, 1882. (No model.)

To all whom it may concern:

Be it known that I, HENRY GROSS, of Tiffin, county of Seneca, State of Ohio, have invented certain new and useful Improvements in Car-Couplers, of which the following is a specification.

My invention relates to that class of car-couplers known as "automatic" couplers, that couple or engage without aid from the brake-man when the cars are run together, and has for its object the construction of a coupler that shall possess the smallest possible number of working parts, whereby the greatest durability and cheapness of construction may be attained; that shall not depend upon accuracy and closeness of fit for successful operation—qualities that would render the action of a coupler very uncertain and problematical; that shall be capable of the simplest and strongest attachment to a car without requiring the removal of previously-applied draw-bars, or making any change whatever in the sill or frame system of the car; that shall be capable of utilizing the common link-and-pin draw-bar as a buffer to secure the proper separation of the cars; that may be readily uncoupled from the side or top of the car, and that shall be absolutely proof against disengagement so long as the cars remain upon the track, while being capable of instant and certain self-disengagement should the cars leave the track upon either side thereof, which is an object desirable of attainment in order to prevent one car, should it leave the track, from drawing others after it.

To these ends my invention consists essentially in a draw-bar adapted to couple automatically by gravity, and to be capable of disengagement laterally while the train is moving, should one car accidentally become derailed or thrown from the track, the precise construction being a broad thin bar secured to the car so as to have a vertical motion, its breadth lying in a horizontal plane, and having hooks formed on its upper and lower surfaces, the drawing-surface of each of which is divided uniformly and completely across its face into two parts by a horizontal offset, causing the part farthest from the bar to overhang the part that joins it to the bar, as hereinafter more fully explained.

The invention further consists in a peculiar

form of bolt with which to secure the draw-bar to the car, and in the manner of attaching said bolt to the car.

The invention further consists in the manner of applying a spring to the draw-bar, and in details of construction which will be hereinafter described, and set forth in the claims.

Referring to the drawings, Figure 1 is a sectional elevation of the contiguous ends of two cars provided with my improved coupler. Fig. 2 is an enlarged sectional elevation of my coupler and fastening device. Fig. 3 is a plan of the same. Fig. 4 is a sectional elevation of my improved coupler, showing a modification in the hook end of same. Fig. 5 is a sectional elevation of coupler, illustrating one manner of attaching draft-spring. Fig. 6 is a plan of the same. Fig. 7 is a transverse sectional elevation on the line *xx*, Fig. 6. Fig. 8 is a longitudinal section in elevation of coupler, illustrating one form of attachment to a car. Fig. 9 is a transverse section on the line *yy* of Fig. 8. Fig. 10 is a plan of coupler as shown in Fig. 8.

Referring to the drawings, A represent a portion of the body of a freight-car having the usual four-wheeled trucks, B. Secured to the under side of the main floor-sills of the car are a pair of sills, C C, having their length disposed in the direction of the length of the car, and between and to these sills is secured the ordinary pin-and-link draw-bar, D. This is the construction of the draft apparatus of an ordinary freight-car, and without changing it in the least particular, which is strongly objected to by railroad officials and master mechanics, I propose to attach my improved draw-bar or automatic coupler in the following manner: To the under side of the old draw-bar sills C C, I secure the short sills E in a transverse position with relation to the car and at a suitable distance apart. They are firmly attached by long heavy bolts *e e*, running entirely through sills C C, and also through the main sills of the car-floor. Secured to these sills E, at points midway of their length, and directly beneath and parallel with the center of the old bar D, is a heavy staple-bolt, F. This bolt has two ends, *f f*, that pass through the sills E, and are provided with retaining-nuts *e e*. In continuation of the ends *f f* the bolt has a central portion, *f'*, lying at right

angles thereto, which, taken in connection with the ends, forms a U-shaped or "staple bolt," as I have heretofore termed it. The bolt is shown in this form in Figs. 4, 5, and 6 of the drawings, with the end portions, f, f' , extending vertically through the sills E from the bottom thereof, and the central portion lying in a horizontal plane, with its length parallel to the direction of length of the car. In Figs. 1, 2, and 10 the bolt is secured to the sills somewhat differently and required to have a slight change of form. The end portion, f , that enters the sill E lying nearest the end of the car passes vertically through the same from the bottom, 15 as before; but the end portion that is secured to the sill E lying farthest from the end of the car enters that sill in a horizontal direction from its front side, and is connected with the horizontal portion f' by an inclined portion, f^2 . 20 In both cases, however, the horizontal portion is suspended some distance below the lower surface of the sills E by making the vertical portions longer than the depth of the sills. To the vertical portion f that extends below the 25 bottom surface of the forward sill, E, I secure the draw-bar G. This bar is made broad and relatively thin—that is to say, the proportion of width to thickness is as about eight to one—and it is provided near its rear end with an 30 aperture, g , to receive the vertical portion f of bolt F. This aperture g may be made of only sufficient size to freely engage the bolt, or it may be elongated in the direction of length of the bar, so as to allow of some longitudinal 35 movement of the bar upon the bolt. When the aperture is reduced to approximately the size of the bolt the draw-bar is designed to pull directly upon the bolt; but when the aperture is elongated the draft is transmitted by a spring 40 from the draw-bar to the bolt, and a yielding connection is secured that will reduce the shock of sudden strains in starting. Formed upon the bolt F is a shoulder, f^3 , to support the bar G above the horizontal portion f' . 45 In the drawings two styles of draft spring H are shown. The spring H in Figs. 4 and 8 is compressed between an abutment, h , upon the top of the draft-bar, back of the bolt F and the forward sill, E, in which case the pull 50 is not upon the bolt, but upon the sill; and the spring in Figs. 5 and 6 is compressed between two heads, I and J, one of which, the head I, is secured to the draw-bar, at the rear of the elongated aperture g in the same, the other 55 head, J, being adapted to move freely in said aperture and press against the rear of bolt F, in which case the pull is upon the bolt. The heads I and J are, for convenience of attachment, constructed in two parts, and the head I 60 is bolted to the bar by the same bolts that hold the two parts together, while the movable head J rests in the slot g , with its flanges extending beyond the slot, so as to embrace the bar, and the bolt that holds the two parts together 65 passes through that portion that rests in the slot. Beyond the rear spring head or abutment the draw-bar is bent slightly downward,

and is provided with a slot, g' , to engage the rear portion of the bolt F and act as a guide to keep the draw-bar parallel with the longitudinal axis of the car, so that there shall be no lateral displacement thereof. 70

In Figs. 8, 9, and 10 a modification in the manner of securing the bolt F to the car is illustrated. In this case but one transverse 75 sill, E, is employed, and both ends of the bolt, which is constructed as shown in Fig. 4, enter it in a vertical direction from the bottom upward, the horizontal portion extending parallel with the direction of length of the sill, 80 and at right angles with the axial length of the car. The rear end of the draw-bar is consequently broadened to accommodate two apertures, g , each of which receives one of the vertical portions f of the bolt, and the spring 85 H and abutment h are located midway between and slightly back of the apertures.

The forward or hook end of the draw-bar is constructed as follows: The bar is extended forward the proper distance, and has formed 90 upon its upper and lower surfaces hooks G' , which, taken together, might be called a "double hook." These hooks are equal in width to the width of the draw-bar, and the metal is beveled forward of them from both top and bottom to a common point, G^2 , that forms the nose or end of the bar, and these inclined surfaces permit one bar to ride upon another in the act of coupling. The vertical drawing-surfaces of the hooks are divided into two 95 portions, 1 and 2, by a horizontal dividing-off-set, 3, the portion 1, which is farthest from the bar, projecting backward beyond the portion 2, that connects it to the bar, so that when two bars are caused to engage the projecting 100 surface 1 of one bar will come in contact with the recessed surface 2 of the other bar. 105

It will readily be seen that when two draw-bars are thus engaged in the act of pulling no jolting or jumping can possibly disengage 110 them, it being necessary to first move the bars backward in a direction exactly opposite to the direction of draft, and then bodily lift one vertically to clear the hook of the other.

The contour of the drawing-surfaces of the 115 hook G' is perfectly uniform horizontally across their face from side to side of the hook, so that they can be disengaged by sliding one laterally out of the other, and at a time when the drawing-surfaces are in contact. They 120 are constructed in this manner so that should a car jump the track on either side its draw-bar would immediately slide out of engagement with the bar of the next car, and thus prevent the runaway car from drawing others 125 after it.

To raise and depress the bar F when desired in the act of uncoupling a crank-rod, K, is journaled to the rear side of sill E, with one crank resting against the top surface of the bar, and the other crank extending to one side of the car, within easy reach of the brakeman. If it is desired to uncouple from the top or 130 platform of the car, a suitable rod or chain may

be connected to the crank-rod K. If so desired the bar G may be adapted to swing laterally upon the bolt F to permit uncoupling, by moving the bar in a horizontal instead of a vertical direction, and in that case the slot g' in the rear end of the bar would be dispensed with and means employed by which the bar could be either held rigidly in a central position or rotated sidewise in either direction at will. In all cases, however, the bars are intended to couple or engage by the action of gravity, one of the bars riding upon and dropping into contact with the other when two cars are brought together. When the bars are adjusted upon the cars the hook ends must invariably rest, when depressed to their lowest position, at a uniform distance above the track upon which the cars run, so that where the car to which a bar is attached is higher than an average the bar must be attached correspondingly low, and where the car is lower than an average height the bar must be attached correspondingly high. If necessary, a means of adjustment may be provided in the shape of a set-screw, that may pass through a lug upon the back side of the front sill, E, and rest against the top side of the draw-bar back of bolt F. By running this screw down against the bar the forward end of the same will be elevated, and if the screw is backed upward the forward end of the bar will be depressed.

It will be observed from the foregoing description that the draw-bar can be attached to cars having the ordinary link-and-pin draw-bar without disturbing the same in the least, and I employ the old draw-bar to act as a "buffer," to take the shock of the cars in coming together, and to keep them separated the proper distance apart.

In most automatic couplers it is necessary to remove the old draw-bar entirely, which is objectionable for many reasons besides cost, and hence my coupler will, with its simple method of fastening, the more readily recommend itself to railroad officials for attachment to old cars.

Owing to the tenon-shaped hook, it is impossible for it to become uncoupled by jarring or jolting when in the act of pulling, and no amount of wear will defeat its operation. The fastening is of the simplest and strongest form possible, and will require no cutting or changing of the car-frame, but simply the boring of a few bolt-holes in order to attach it.

Having thus described my invention, what I claim, and desire to secure by Letters Patent, is—

1. An automatic car-coupling consisting of a broad thin bar, G, secured to the car to have

vertical play, and having hooks formed upon its upper and lower sides, the drawing-surfaces of each of which are divided uniformly and completely across their faces into two parts, 1 and 2, by a horizontal offset, 3, the portion 1 overhanging the portion 2, that joins it to the bar, all arranged to operate substantially as described.

2. An automatic car-coupler consisting of a flat bar, G, having at its end a double hook, G', the drawing-surfaces of which extend vertically from the upper and lower faces of the bar, and each of which drawing-surfaces is divided into two portions, 1 and 2, by a horizontal offset, 3, when one of the drawing-surfaces is formed upon the bar in advance of the other, and the bar intermediate is curved, so as to bring both hooks more nearly in line with the body of the bar, substantially as and for the purpose specified.

3. In combination with the bar G of an automatic car-coupler adapted to rise and fall vertically in the act of coupling, the staple-bolt F, passing vertically through an aperture or apertures, g, in the bar, and secured to the transverse sills E, bolted against the under side of the car, substantially as and for the purpose described.

4. In combination with the draw-bar G of an automatic car-coupler, and the staple-bolt F, the transverse sills E, secured to the under side of the sills C C, to which the ordinary draw-bar is secured, substantially as and for the purpose specified.

5. The draw-bar G, staple-bolt F, and transverse sills E, in combination with the ordinary link-and-pin draw-bar, D, and sills C C, substantially as and for the purpose specified.

6. In combination with staple-bolt F, secured by sills E to the under side of the car, the draw-bar G, having opening g to secure it to one end of the bolt, and slot g' to engage the other end of the bolt and act to keep the draw-bar in a central position, while permitting the necessary vertical motion of the bar, substantially as and for the purpose specified.

7. In combination with staple-bolt F, secured to the car-sills, the draft-bar G, having elongated openings g g', fixed head I, sliding head J, and intermediate spring, H, substantially as and for the purpose specified.

8. In combination with bar G, the staple-bolt F, having shoulder f³, substantially as and for the purpose specified.

In testimony of which invention I hereunto set my hand this 28th day of August, 1882.

HENRY GROSS.
